UNITED STATES PATENT OFFICE.

JOSHUA W. JONES, OF HARRISBURG, PENNSYLVANIA; COMMONWEALTH TRUST COMPANY, EXECUTOR OF SAID JOSHUA W. JONES, DECEASED, ASSIGNOR TO JONES COMPANY, OF HARRISBURG, PENNSYLVANIA, A FIRM COMPOSED OF JOSEPH R. JONES, OF PHILADELPHIA, PENNSYLVANIA, J. MILEY JONES, ROBERT ROSS JONES, AND JOHN PAUL JONES, ALL OF HARRISBURG, PENNSYLVANIA, AND WILLIAM D. JONES, OF NEW YORK, N. Y.

COIN-HOLDER OR CHANGE-MAKER.

1,172,607.

Specification of Letters Patent. Patented Feb. 22, 1916.

Application filed January 23, 1914. Serial No. 814,964.

To all whom it may concern:

Be it known that I, JOSHUA W. JONES, a citizen of the United States, residing at Harrisburg, in the county of Dauphin and

5 State of Pennsylvania, have invented certain new and useful Improvements in Coin-Holders or Change-Makers; and I do hereby declare the following to be a full, clear, and exact description of the same, reference 10 being had to the accompanying drawings, forming part of this specification, and to the figures and letters of reference marked thereon.

The present invention relates to devices 15 for holding coins in a convenient position for being withdrawn in the making of change, devices of this character being especially designed for use by street car conductors and others who are called upon at 20 frequent intervals to return change to passengers or customers, and, therefore, find it desirable to have the coin holding devices supported in a convenient position on the body, usually by means of a belt or other 25 attaching appliance.

The objects of the invention are to provide a simple and convenient form of device composed of few parts, easily and cheaply manufactured and assembled and 30 having the capacity for being combined in a connected series of holders or of being utilized in the form of separate holders, thus permitting the individual user to suit his own taste in the number of holders employed.

The invention consists in certain novel 35 details of construction and combination and arrangement of parts, all as will be now described and pointed out particularly in the 40 appended claims.

Referring to the accompanying drawings, Figure 1 is a perspective view of a connected pair of coin holders embodying the present improvement; Fig. 2 is a similar 45 view looking at the rear side of the pair of holders shown in Fig. 1, the belt being omitted from both Figs. 1 and 2. Fig. 3 is a section in a central vertical plane through one of the holders; Fig. 4 is a bottom plan view of one of the holders; Fig. 5 is a plan view of a blank from which the 50 frame of the device is formed; and Fig. 6

is a detail perspective of the preferred form of coin slide.

Like letters of reference in the several 55 figures indicate the same parts.

The body portion of each holder, lettered A in the accompanying drawing, is, as is usual in this class of devices, of cylindrical form, having at the top means whereby coins 60 of the desired denomination may be inserted and at the bottom means whereby the coins may be withdrawn one at a time. The cylindrical body is mounted on a frame, which in the present instance is preferably 65 formed up from a piece of sheet metal with means whereby the holder may be readily and conveniently attached to a supporting belt, a portion of said frame extending below and constituting the bottom of the 70 holder or receptacle and a portion extending over the top or partly over the top of the receptacle, and where a hinged cover is employed, adapted for the attachment of 75 said cover thereto.

Referring to Fig. 5 it will be seen that the blank from which the frame is formed, embodies a central vertical bar B and on each side of said central vertical bar are off-set arms B' extending downwardly from the upper portion of the frame, and other arms B² 80 extending upwardly from the lower portion of the frame. The arms B', however, are of considerably greater length than the arms B² and both pairs of said arms are 85 off-set rearwardly with respect to the central bar to form a belt receiving space, as shown in Fig. 3. The proximate ends of the oppositely disposed bars are preferably spaced apart a sufficient distance to admit 90 the edge of the belt between them and the device is applied to a belt by slipping it under the low ends of the upper arms, and when pushed up into the space between said arms and the center bar, the lower edge of 95 the belt is slipped in beneath the lower arms. The bottom semi-circular portion of the blank is centrally slotted at b and bent forwardly at right angles to the center bar, thus constituting the bottom of the receptacle 100 formed by the body A. Said body is at the bottom provided with a front opening a of a width to permit of the passage of a single coin, and it is held in place in the

frame by ears a' at the back which are passed through apertures b' in the center bar and upset or bent over against the outer face of said bar, while at the bottom ears a^2 extend through slots or openings in the bottom of the frame which are similarly upset or bent over on the outer side of the frame, thus clamping the frame and receptacle rigidly in position.

- 10 Portions of the metal struck up to form the apertures in the center bar are preferably curled to form transverse eyes C at the back of the frame near the top and bottom thereof, said eyes being adapted for the reception of lateral wires or rods D for connecting several holders to form a unitary series, and it is obvious that the purchaser may, by means of such wires, connect the desired number of holders in a series or 20 block adapted for his particular use, the wires being cut to the desired length and the ends bent to retain the holders side by side.

The mechanism for withdrawing the coins from the bottom of the holder embodies a bottom slide E which when in normal position in the device is preferably of such dimensions as to be substantially coextensive with and fit the bottom of the receptacle. When retracted it constitutes a support 30 upon which the coins rest. At the back end of the slide there is an upwardly extending projection e of a thickness which is slightly less than the thickness of the coin to be ejected and this projection is formed with 35 its forward edge inclined with respect to the line of movement of the slide whereby it will have a tendency to push the coin off to one side. The escape of the coins through the opening is normally prevented by a 40 curved projection e^2 on the front of the slide, preferably located on the side of the slide opposite that toward which the rear projection is inclined. Thus a coin lying on the slide is carried bodily out of the bottom 45 of the receptacle and held in such position on the slide itself but with its forward portion projecting a sufficient distance to be conveniently grasped by the thumb of the user, or if the slide be advanced with a sharp 50 movement it will be ejected and free from the slide dropping into the hand of the user. The slide is manipulated by a downwardly extending projection F working in the slot b in the bottom of the frame, the forward 55 movement being limited by stops g' on the frame and the slide being drawn back or held yieldingly in its normal position by a spring G. In the preferred arrangement the spring G is a coil spring which is swiveled at its forward end to the projection F and at its rear end is threaded through an ear or projection g formed by turning down a portion of the frame, the turned down portion leaving an aperture or slot into which 60 the rear end and projection on the slide may

pass when the slide is in normal position, as shown clearly in Fig. 3. The portion of the spring G projecting in rear of the ear through which it is threaded may be provided with a head or other convenient means whereby it may be rotated in the threaded projection, thus constituting a ready and convenient means for adjusting the tension of the spring and insuring the quick return of the slide to normal position. The slide 70 itself may furthermore be provided at the point where the coin leaves the same, with a cut-away or recessed portion I to facilitate the disengagement of the coin therefrom by the thumb of the operator whenever the slide is drawn forward through the manipulation of the first finger, the operation of advancing the slide to draw a coin out being a natural one for the right hand of the user, and the coin being presented in a convenient 80 position to be pinched downwardly by the thumb and to be received in the hand under the guidance of the thumb.

At the top of the holder or receptacle, the frame extends forwardly and rests on the upper edge of the receptacle so as to form an inclosing frame between the top and bottom of which the receptacle is clamped or held, and while this top or upper portion of the frame, lettered K in the drawing, 90 may form the entire top of the receptacle, and be slotted, if so desired for the admission of coins, as in my prior application Serial No. 723,538, filed October 2, 1912, in the present structure it extends only a part 95 of the distance over the top of the receptacle and its forward edge is formed into pintle eyes i adapted for the reception of a pintle on which a hinged cover L is mounted. The cover is normally held in closed position by 100 a coil spring mounted on the central portion of the pintle and having its ends extended in opposite directions over the top and hinged cover, as will be readily understood from Fig. 1.

In use, the device is designed to be carried by a belt which is threaded through the arms at the rear of the device, as heretofore described, a series of the devices being connected by the rods or wires passing through 115 eyes on the rear side thereof. The wires being more or less pliant, may be bent for giving a curve to the several connected devices to fit the body of the user; and when in position at the waist line it will be seen 120 that the finger of the right hand will naturally fall into position for coöperation with the downwardly extending projection of the slide of each of the holders. Owing to this natural position of the hand in operating 125 the device, it seldom becomes necessary for the user to look at the device for he may manipulate it by drawing the desired slide forward any desired number of times and thus discharge into his hand under the guid- 130

ance of his thumb any desired number of coins or coins from any one or the other of the receptacles.

Having thus described my invention, what I claim and desire to secure by Letters Patent of the United States, is,—

1. In a coin holder and change maker, the combination with a cylindrical coin receptacle having openings at top and bottom for the entry and discharge of coins, of a frame plate having its lower portion extended forwardly at substantially right angles to form the bottom of the receptacle and its upper portion extended forwardly at substantially right angles, a top for the receptacle adapted to be pivotally mounted on the forwardly extended upper portion of the frame, and means connecting the receptacle and frame together at the back and bottom respectively.

2. In a coin holder and change maker, the combination with a cylindrical coin receptacle having openings at top and bottom for the entry and discharge of coins, of a frame having its lower portion extended forwardly at substantially right angles to form the bottom of the receptacle, parallel side arms formed integral with the frame and intermediate the ends thereof, and projecting downwardly from the top of the frame on opposite sides of the center, and bottom side arms formed intermediate the lower extremities of the first mentioned arms and the forwardly bent lower portion of the frame and projecting upwardly from the forwardly bent lower portion of the frame to coöperate with the top arms in retaining a belt.

3. In a coin holder and change maker, the combination with a cylindrical coin receptacle having openings at top and bottom for the entry and discharge of coins, of a frame having its lower portion extended forwardly at substantially right angles to form the bottom of the receptacle, parallel side arms formed integral with the frame and intermediate the ends thereof, and projecting downwardly from the top of the frame on opposite sides of the center, and bottom side arms formed intermediate the lower extremities of the first mentioned arms and the forwardly bent lower portion of the frame and projecting upwardly from the forwardly bent lower portion of the frame to coöperate with the top arms in retaining a belt, said arms being offset toward the rear to admit the belt between them and the body of the frame.

4. In a coin holder and change maker, the combination of a frame plate having its lower end bent forwardly at substantially right angles and a plurality of slots in both portions of said frame member, of a cylind-

rical coin receptacle adapted to seat on the forwardly bent portion of the frame member and having openings at the top and bottom thereof for the entry and discharge of coins, a plurality of ears on said receptacle each adapted to register with one of said slots in the frame to extend therethrough and engage the outer side of the frame whereby the two members are connected together by the coöperation of the ears with the slots.

5. In a coin holder and change maker, the combination with a cylindrical coin receptacle having a discharge opening at the front, of a slide adapted to reciprocate in a straight line and co-extensive with the bottom of the receptacle and on which the coins are supported in the receptacle when the slide is retracted, a projection on the front of the slide for preventing the escape of coins through the opening the edge of the slide being recessed adjacent said projection and a projection on the back of the slide for engaging and advancing the lower coin through the opening in unison with the forward movement of the slide, said projection having an inclined face for imparting a lateral movement to the coin while it is being ejected.

6. In a coin holder and change maker, the combination with a cylindrical coin receptacle having a discharge opening at the front, of a slide adapted to be moved in a straight line toward and from the discharge opening, said slide being co-extensive with the bottom of the receptacle and on which the coins are supported when the slide is retracted, a projection on the front of the slide for holding coins against outward movement through the opening, and an inclined faced projection on the back of the slide for advancing the bottom coin with the slide and imparting a lateral movement thereto.

7. In a coin holder and change maker, the combination with a coin receptacle having an opening for the discharge of coins at its lower end and a slot extending across its bottom, and a slide adapted to be reciprocated in said slot for discharging coins through the opening, said slide having a projection extending downwardly through said slot and below the bottom of the receptacle, of a coil spring for retracting the slide, a swivel connection between said spring and projection and a lug integral with the bottom of the receptacle, said lug having a screw threaded opening in which the spring is adjustably held.
